UNITED STATES PATENT OFFICE.

EPPA H. RYON, OF WALTHAM, MASSACHUSETTS, ASSIGNOR TO CROMPTON & KNOWLES LOOM WORKS, A CORPORATION OF MASSACHUSETTS.

WEFT-REPLENISHING LOOM.

1,074,530.

Specification of Letters Patent. Patented Sept. 30, 1913.

Application filed March 24, 1913. Serial No. 756,356.

To all whom it may concern:

Be it known that I, EPPA H. RYON, a citizen of the United States, residing at Waltham, in the county of Middlesex and 5 State of Massachusetts, have invented certain new and useful Improvements in Weft-Replenishing Looms, of which the following is a specification.

My invention relates to automatic weft 10 replenishing looms, and particularly to the magazine of a weft replenishing loom, which holds the bobbins or filling carriers, which are automatically supplied to the shuttle at the magazine end of the loom, 15 upon the practical or substantial exhaustion of filling in the active shuttle.

The object of my invention is to provide 20 a magazine capable of containing a large number of bobbins or filling carriers, preferably of the same color or character, which bobbins are successively moved toward the discharging end of the magazine, and the first bobbin is moved into a position 25 under the transerrer, preparatory to being transferred into the active shuttle to take the place of the substantially exhausted bobbin therein, on the indication of the filling detecting mechanism.

My improved magazine has a spiral 30 guide-way or groove for the bobbins, starting from the central part of the magazine, and also has means for moving the bobbins in the groove, toward the discharging end of the magazine, and into a position 35 to be transferred.

My improved magazine consists preferably of a rotatably mounted part, comprising two disks, each having a spiral guide-way or groove therein, one for the butts, 40 and the other for the tips of the bobbins, and a stationary part, leading from the discharging end of said rotatably mounted part, and a spring actuated pusher for moving the bobbins toward the discharging 45 end of the magazine, and into a position to be transferred. I also provide means, combined with the magazine, to support the filling threads in a central position relative to the magazine, and separate means to hold 50 the ends of said threads.

My invention consists in certain novel features of construction of my improvements as will be hereinafter fully described.

I have only shown in the drawings a de-

tached portion of a weft replenishing loom, 55 and transferring mechanism, with my improved magazine combined therewith, sufficient to enable those skilled in the art to understand the construction and operation thereof.

Referring to the drawings:—Figure 1 is a side view of some parts of a weft replenishing loom, and my improved magazine attached thereto; the magazine is shown in section, on line 1, 1, Fig. 2, looking in the direction of arrow *a*, same figure. The lay and stationary shuttle box thereon are also shown in section. Fig. 2 is a section, on line 2, 2, Fig. 1, looking in the direction of arrow *b*, same figure; some of the parts shown in the lower part of Fig. 1 are not shown in this figure. Fig. 3 is an inner end view of the magazine, looking in the direction of arrow *c*, Fig. 2. Fig. 4 is an outer end view of the magazine, looking in the direction of arrow *a*, Fig. 1. Fig. 5 corresponds to Fig. 3, but shows the magazine in a different position. Fig. 6 shows the pusher mechanism shown in Fig. 3, detached, and with its cover removed, and, 70 Fig. 7 is a plan view of the parts shown in Fig. 6, looking in the direction of arrow *d*, same figure.

In the accompanying drawings, 1, Fig. 1, is a portion of a loom side or end frame, 2 85 is the lay with a single shuttle box 3 thereon, containing a shuttle 4, which carries a bobbin or filling carrier 5. A feeler or filling detector, of any usual construction, not shown, is adapted to enter through the opening 4' in the front side of the shuttle 4 to engage the filling on the filling carrier 5, and to operate, through intermediate connections, not shown, the upright lever 6, which has its hub 6' secured on a rock shaft 7, which is suitably mounted in bearings on the filling detector bed, not shown. The upright lever 6 has pivotally connected to its upper end one end of a rod 8, the other end of said rod 8 is adapted to bear against a lug 9' on a downwardly extending latch 9, which has its hub pivotally mounted on a stud 10 on a transerrer arm 11. A helically coiled contraction spring 12 has one end connected to the lug 9', and its other end 105 connected to the rod 8, and acts to yieldingly hold the end of the rod 8 against the lug 9'. The latch 9 has its lower end hooked

at 9", and is adapted to be moved into the path of and be engaged by the hook end 13' on the upwardly extending bar 13. An up and down movement is imparted to the upright bar 13 by mechanism on the loom, not shown, to operate the transerrer arm 11, all as fully shown and described in the United States Letters Patent, No. 1,032,709. All of the above mentioned parts may be of the usual and well known construction.

I will now describe my improvements in the magazine for the bobbins or filling carriers. Rigidly connected to the side 1 of the loom is a stand 14, which carries a stud 15, see Fig. 1, on which is pivotally mounted the hub 11' of the transerrer arm 11, in the usual way. An upwardly extending arm on the stand 14 has a boss 14', see Fig. 2, in which is secured, by a nut 16, a horizontally extending stud or shaft 17, which has loosely mounted thereon the magazine for bobbins or filling carriers 5. The magazine consists in this instance of the inner end 18, see Fig. 2, for the butt 5' of the bobbins 5, and the outer end 19 for the tips 5" of the bobbins 5. The inner end 18 has its hub 18' loosely mounted on the stud 17, and extending outwardly from said hub 18' is a sleeve 18", which has mounted on its outer end and fast thereon the hub 19' of the outer end 19 of the magazine, which end holds and guides the tips 5" of the bobbins 5. The inner end 18 of the magazine is provided with a guideway for the butts 5' of the bobbins 5, which guideway consists of a groove 18''' which in this instance extends in spiral form from the center of the magazine to the outer open end 18^a, see Fig. 1. The outer end 19 of the magazine is also provided with a corresponding guideway or groove 19''' of spiral form, for the tips 5" of the bobbins 5. The guideway or groove 19''' extends from the center of the magazine to the open end 19^a, see Fig. 4.

The bobbins 5, which are inserted into the guideways 18''' and 19''' of the magazine and loosely held therein, are forced from the center of the magazine toward the open end, in this instance by a pusher. The pusher for the bobbins, see Figs. 1 and 2, consists in this instance of a bar or arm 20, which extends loosely through a groove 18''' in the inner end 18 of the magazine, and is adapted to engage the innermost bobbin 5 therein. The bar or arm 20 is provided with a guide block 20' on its outer end, which is adapted to slide freely on two parallel arms 21, see Figs. 6 and 7. The arms 21 extend outwardly from a cylindrical case 22, which in this instance is centrally located on the magazine and loosely mounted on the hub 18' of the inner end 18 of the magazine. A spiral spring 23 is in this instance located within the hollow part of the case 22, and acts to yieldingly move the arms

21 in one direction, and to force the bar 20 thereon against the innermost bobbin 5 in the magazine, see Fig. 1.

A ratchet gear 24, which in this instance is made integral with the arms 21, is adapted to be engaged by a lever 25, as shown in Fig. 5, to hold the ratchet 24, and the operating arms 21 thereon. The lever 25 has its hub 25' loosely mounted on a stud 26 on a stand 14, see Fig. 5. A helically coiled contraction spring 27 acts to yieldingly hold the lever 25 out of engagement with the ratchet gear 24, as shown in Fig. 3, or in engagement with the ratchet gear 24, as shown in Fig. 5.

The bobbins 5, which are forced toward the opening 18^a of the magazine, drop with their butts 5' into a chute or guideway 14^a, see Fig. 1, which in this instance is made integral with the stand 14, which chute is adapted to guide the bobbins 5 downwardly, and under the transerrer arm 11. A spring actuated latch 28 has its lip 28' extend under the lowest bobbin, and is adapted to hold the lowest bobbin in place, and yieldingly move out of the path of the butt of the bobbin, when the lowest bobbin is to be transferred. The latch 28 has its hub 28'' loosely mounted on a stud 29 on the stand 14, see Fig. 3, and a torsion spring, not shown, acts to yieldingly move the latch 28 into position. Transverse rods 30, see Figs. 1, and 4, with tubes 30' thereon, are adapted to connect the inner chute 14^a with the outer chute 31, which outer chute is adapted to form a guideway for the tips 5" of the bobbins 5, which drop toward the lower discharging end of the magazine. The lowest bobbin 5 rests with its tip 5" upon a latch 32, which is loosely mounted on a stud 33, and is yieldingly held in position by a flat spring 34, see Fig. 4. The outer end 19 of the magazine is provided with a spirally shaped opening or slot, through which the filling threads 5^a extend. The filling threads 5^a are guided over a guide frame 35, and extend downwardly to a thread holder 36, so that the ends of the thread may be wound thereon, see Fig. 4.

In Fig. 1 is shown the spiral magazine in its operating position, after it has been supplied with bobbins or filling carriers 5, which are to be successively transferred from the magazine to the active shuttle upon the substantial exhaustion of filling in the active shuttle. The magazine is in this instance held in its position by a spring actuated latch 37, see Fig. 1, which has its hub loosely mounted on the transverse tube 30' on the rod 30, see Fig. 1. The upper end 37' of the latch 37 is hook shape, and is adapted to engage with an extension 18^b on the outer edge of the inner end 18 of the magazine.

When it is desired to refill the magazine,

after it has been emptied of the bobbins or filling carriers, the latch 37 is disengaged from the extension 18^b, to enable the magazine to be turned one-half of a revolution on 5 the bolt 17, until the bar 38 on the magazine rests against a stop 14^b on the chute extension 14^a on the stand 14, as shown in Fig. 5. A new supply of bobbins or filling carriers is inserted at the open end of the magazine at 10 18^a, and 19^a, and the pusher, slidably held on the arms 21, is moved inwardly and toward the center of the magazine, while the ratchet gear 24 is retained and locked by the latch 25.

15 It will be understood that the details of construction of my improvements may be varied if desired.

Having thus described my invention, what I claim as new and desire to secure by Letters Patent is:—

20 1. In a weft replenishing loom, a magazine for bobbins or filling carriers, having a spiral guide-way or groove for the bobbins, starting from the central part of the magazine, and a pusher to engage and move the bobbins toward the discharging end of the magazine and under the transferrer.

25 2. In a weft replenishing loom, a magazine for bobbins or filling carriers, having a spiral guide-way or groove for the bobbins, and means to move the bobbins in said guide-way or groove toward the discharging end of the magazine, and into a position to be transferred.

30 3. In a weft replenishing loom, a rotatably mounted magazine for the bobbins or filling carriers, having a spiral guide-way or groove for the bobbins, and means to move the bobbins in said groove toward the discharging end of the magazine, and into a position to be transferred.

35 4. In a weft replenishing loom, a magazine for bobbins or filling carriers, comprising a rotatably mounted part having a spiral guide-way or groove, and a stationary part having a guide-way or groove, and means to push the bobbins through the spiral groove and the stationary groove, and into a position to be transferred.

40 5. In a weft replenishing loom, a maga-

zine, having a stationary discharging end, and a rotatably mounted part having a spiral guide-way or groove for the bobbins, and means to move the bobbins in said groove or guide-way toward the discharging end of the magazine, and means to connect the discharging end of said rotatably mounted part with said stationary discharging end.

6. In a weft replenishing loom, a magazine for bobbins or filling carriers, having a stationary discharging end, and a rotatably mounted part with a spiral groove or guide-way for the bobbins, said rotatably mounted part adapted to be turned on its center to be refilled and means to move the bobbins in said groove or guide-way toward the discharging end of the magazine.

7. In a weft replenishing loom, a magazine for bobbins or filling carriers, having a stationary discharging end, and a rotatably mounted part, with a spiral groove or guide-way, said rotatably mounted part adapted to be turned on its center, to be refilled, and a spring actuated pusher for the bobbins, to move the bobbins toward the discharging end of the magazine and under the transferrer.

8. In a weft replenishing loom, a magazine for bobbins or filling carriers, having a spiral guide-way or groove for the bobbins, and a spring actuated pusher to engage and move the bobbins toward the discharging end of the magazine and under the transferrer, and means for holding said pusher in an inoperative position when the magazine is being filled.

9. In a weft replenishing loom, a magazine for bobbins or filling carriers, having a spiral guide-way or groove for the bobbins, and means to move the bobbins in the groove toward the discharging end of the magazine, and into a position to be transferred, and means to support the filling threads from the bobbins in a central position, and separate means to hold the ends of the filling threads.

EPPA H. RYON.
